DESIGN FOR A SHADE-PULL

John R. Huthsing, St. Louis, Mo.

Application April 16, 1934, Serial No. 51,423

Term of patent 3½ years

To whom it may concern:

Be it known that I, JOHN R. HUTHSING, a citizen of the United States, residing at 4035 Eichelberger Street, in the city of St. Louis, State of Missouri, have invented a new, original and ornamental Design for Shade-pulls, of which the following is a specification, reference being had to the accompanying drawing, forming part thereof.

Fig. 1 is a front elevation, Fig. 2 a side elevation, and Fig. 3 a rear elevation of a shade-pull, showing my new design.

I claim:

The ornamental design for a shade-pull, as shown.

JOHN R. HUTHSING.
